UNITED STATES PATENT OFFICE.

JACOB F. WILLIAMSON, OF ST. LOUIS, MISSOURI.

CHAIN AND BUTTON FOR PUMPS.

SPECIFICATION forming part of Letters Patent No. 785,140, dated March 21, 1905.

Application filed July 11, 1904. Serial No. 216,003.

To all whom it may concern:

Be it known that I, JACOB F. WILLIAMSON, a citizen of the United States, residing at St. Louis, State of Missouri, have invented certain new and useful Improvements in Chains and Buttons for Pumps, of which the following is a specification containing a full, clear, and exact description, reference being had to the accompanying drawings, forming a part hereof.

My invention relates to improvements in chains and buttons for pumps; and it consists of the novel features herein shown, described, and claimed.

15 In the drawings, Figure 1 is a perspective showing a piece of chain and a button. Fig. 2 is a perspective of the pump-head and chain. Fig. 3 is a vertical sectional detail of the parts shown in Fig. 1.

20 Referring to the drawings in detail, my improved chain and button comprises the button-body 5, which is substantially pear-shaped in elevation, there being an annular groove 6 around the largest part of the body and there 25 being a pocket 7 formed from the upper end of the body, the rubber gasket 8 removably mounted in the annular groove 6, the chain-link 9 extending through the body 5, one eye of the chain being below the body 5, the other 30 eye of the chain being in the pocket 7, so as to mount the body 5 upon the chain, and the chain-link 10 connecting the chain-links 9 together, there being a pocket 11 formed downwardly in the upwardly-extending end of the 35 link.

The chain is mounted in the pump-head 12 in the ordinary way to be operated by the crank 13. The chain and buttons pass upwardly through the tube to carry water to the 40 discharge-spout 14, and as the crank is operated to operate the chain the pockets 7 and 11 will be filled with water and will be carried upwardly through the water-chamber 15, over the sprocket-wheel 16, and will be discharged 45 back into the well or cistern. Then as the empty pockets descend into the water they

will be filled with air and this air will be carried downwardly to the bottom of the water, and as soon as the pockets are turned right side up the air will be discharged into the 50 water.

The principal object of my invention is to aerate and purify the water, and this process is performed by discharging the water from the pockets back into the well or cistern 55 through the air and by carrying the pockets full of air down into the bottom of the water and discharging it into the water.

Another feature of great importance in my invention is the removable gasket. When 60 these gaskets become worn, a link of the chain may be opened, the worn gaskets removed, and new ones supplied.

The gaskets are flat on the bottom and have substantially vertical walls extending upwardly from the bottom, and the upper sides of the gaskets are round, as shown in cross-section in Fig. 3.

I claim—

In a chain and button for pumps: the button-body 5 pear-shaped in elevation and having an annular groove 6 around its upper end and largest diameter, and there being a pocket 7 extending downwardly from its upper end; the rubber gasket 8 mounted in the groove 6; 70 said gasket being flat on its bottom and having a substantially vertical inner wall and the upper sides of the gasket being rounded; the chain-link 9 extending through the body 5, the upper eye of the chain-link being in the 75 pocket 7; and the lower eye of the chain-link being below the body and the chain-link 10; there being a pocket 11 extending downwardly in the upwardly-extending end of the link 10; 80 substantially as specified.

In testimony whereof I have signed my name to this specification in presence of two subscribing witnesses.

JACOB F. WILLIAMSON.
